VOLTAGE MULTIPLIER

Application filed December 20, 1929. Serial No. 415,582.

Our invention relates to voltage multipliers, or range-changing devices, and particularly to self-contained portable units of this character for co-operation with portable 5 watt-hour meters.

One object of our invention is to provide a device of the above-indicated character that shall be simple and durable in construction, economical to manufacture and effective in its operation.

Another object of our invention is to provide a variable-impedance device for changing the voltage-operating range of a standard 10 watt-hour meter without varying or altering the meter structure in any respect.

Another object of our invention is to provide a self-contained, compact, neat and readily portable voltage-multiplier unit.

20 A further object of our invention is to provide a voltage multiplier that shall embody various novel features of construction, such as a casing therefor, a variable reactor and a variable resistor.

25 With such objects in view, as well as other advantages which may be incident to the utilization of the improvement, the invention consists in the parts and combinations thereof hereinafter set forth and claimed, 30 with the understanding that the several necessary elements constituting the same may be varied in proportion and arrangement without departing from the nature and scope of the invention.

35 Figure 1 of the accompanying drawings, is a diagrammatic view of a device embodying our invention;

Fig. 2 is a front elevational view of the 40 device of our invention, the front cover being removed for clearness; and

Fig. 3 is a view of the structure of Fig. 2, taken at right-angles thereto substantially along the line III-III thereof.

45 Referring to Fig. 1, the device comprises, in general, a magnetizable core member 2, a magnetizable keeper 3, a stationary member or bracket 4 on which the keeper 3 is adjustably mounted, as by a screw 6, terminals 7 and 8, and a variable resistor 10 and a single

coil 12 that are connected in series relation between the terminals 7 and 8.

Referring to Figs. 2 and 3, in which corresponding parts are designated by corresponding reference characters, the device 55 further comprises a casing including front and rear walls or plates 14 and 15, respectively, a side wall 17, standards 18 for connecting the walls 14 and 15 and a bail or handle 19.

60 The walls 14, and 15 are similarly constructed of insulating material, such as paper or other fiber impregnated with a phenolic condensation product, and are provided with perimetral rabbet grooves 20 and integral 65 bosses 21. The rear wall 15 constitutes a single means for supporting all of the working parts of the device, as will hereinafter appear.

65 The standards 18, preferably of insulating 70 material similar to that of the walls 14 and 15, extend between corresponding bosses 21 on these walls, respectively, in fixed relation to the rear wall 15 and in removable relation to the front wall or cover member 14, as by 75 the use of removable screws 23.

75 The side wall 17, also of a material similar to the front and rear walls, is of tubular form surrounding the standards 18 and fitted, at 80 its ends, into the rabbet grooves 20.

85 The bracket 4, preferably of non-magnetic material, such as brass, is of substantially U-shape, as viewed in front elevation, having its leg ends 24 secured to the rear wall 15, as by screws 25, an intermediate portion 27, offset from the rear wall for positioning the core member 2, and a horizontal-plane bottom portion 28 further offset from the rear wall for supporting and properly positioning the keeper 3 relative to the core 2.

90 The core member 2, of a usual laminated type, is of substantially E-shape disposed face-down and spaced above the portion 28 in flat-plane side relation to the walls 14 and 15 95 and to the portion 27 of the bracket 4, to which it is secured by screws 30 which extend through lateral outward projections 31 on the outer legs 32 of the core. Lateral inward projections 34 on the outer legs 32 cooperate 100

with the main or intermediate leg 35 to provide a pair of relatively short air gaps 37.

The resistor 10 comprises principal and auxiliary spools 38 and 39, respectively, on

5 the former of which the major portion of a resistor or wire 40 is wound. The spools are of dielectric material, such as porcelain, and are held in position by screws 41 and 42 which extend into the rear wall plate 15 of the

10 casing.

Only a relatively short length of the wire 40, at one end thereof, is normally wound on, or secured to, the auxiliary spool 39, and a lead 44 from the coil 12 is soldered to a portion of the wire extending between the spools 38 and 39.

15 A series circuit through the device extends from the terminal 7, through a conductor 46, to the spool 38, through the latter and 20 through the lead 44 to the coil 12 and, from the coil 12, through a conductor 47, to the terminal 8.

The keeper 3 comprises a laminated discoidal portion that is carried by the screw 6 25 which is mounted in the portion 28 of the bracket 4.

By turning the screw 6, the keeper 3 may be adjusted in the direction of the core legs relative to both air gaps 37. A screw 49 is 30 provided to lock the screw 6 in adjusted position.

The terminals 7 and 8 are similar and each 35 comprises a conducting base portion 33, on the upper side of the tubular wall portion 17, having a screw or stud portion 54 extending through said side, an insulating head or handle portion 36 having a conducting lower portion 53, a conducting shank or screw portion 43 disposed in the base portion 33, a terminal 40 element 45 for soldering to one of the conductors 46 and 47, and nuts 48, on the screw portion 54, between which the element 45 is held in position.

Notches 51, in the base portions 33, serve to 45 position conductors (not shown) for clamping between the conducting portions 33 and 53, which conductors are to be connected to the meter or other structure with which the device of our invention is adapted to cooperate.

The bail or handle 19, preferably of insulating material, is pivotally mounted on the sides of the wall portion 17, as by pins 52, whereby the unit may be transported, and 55 the bail may be moved from the vicinity of the terminals 7 and 8 when it is desired to connect or disconnect conductors relative thereto.

The device, as a whole, constitutes a series 60 impedance for absorbing part of the voltage impressed on the voltage coil of a watthour meter or other device; the core 2, the coil 12 and the keeper 3, together, constituting an adjustable reactor, and the spools 38 and 39, with the lead 44, constituting an adjustable 65 resistor.

By adjusting the reactor and resistor, it is possible to use a meter on double voltage without producing any error in ratio or phase angle.

The reactor is adjusted by moving the keeper 3, relative to the air gaps 37, to increase or decrease the reactance of the total magnetic circuit which permits a variation of the reactance of the coil 12.

The resistor 10 may be adjusted by first 75 heating and disconnecting a solder joint 50 between the lead 44 and the resistor wire 40, then releasing the screws 41 and 42 to wind the wire 40 back and forth between the spools 38 and 39, by turning the spools, then resoldering the lead 44 to a new position on the resistor wire 40 and tightening the screws 41 and 42. The portion of the wire 40 which has previously been soldered to the lead 44 and released therefrom may be touched over with 80 shellac or otherwise insulated for winding back to the spool 38 or forward to the spool 39. This adjustment permits the power factor of the coil 12 to be varied at will.

The device comprises a simple, neat, compact, self-contained, portable unit for cooperation with a meter extraneous thereto and, although it embodies elements that have individually been heretofore employed in other apparatus in various ways, it is not known 90 to us that the elements have ever been combined in a manner so effective for the purpose for which the unit is intended or that any portable self-contained unit of this character has ever been suggested. So far as we 100 are aware, it is a new entity in the electrical measurement field and is, in general, an improvement which facilitates operation in that field and has other advantages not heretofore attained.

105 We claim as our invention:

1. A self-contained voltage-multiplier unit comprising a reactor including a laminated core of substantially E-shape, a coil on the intermediate leg of the core and a laminated discoidal keeper adjustable relative thereto in the direction of said leg, a spool resistor and a single supporting means for the reactor and the resistor.

2. A self-contained voltage multiplier unit 115 comprising an insulating support, a non-magnetic bracket of substantially U-shape having its leg end secured thereto and its loop end displaced therefrom, a magnetizable core of substantially E-shape providing a pair of air gaps and secured to said bracket, a coil on the intermediate leg of the core, a magnetic keeper spanning both of said gaps and adjustably related thereto, and a resistor mounted on said support.

3. A voltage multiplier comprising an insulating casing, a non-magnetic bracket of substantially U-shape having its leg ends secured to the rear wall of the casing and its loop end displaced from said wall, a mag- 125

130

netic core of substantially E-shape secured to said bracket with its legs extending downwardly, a coil on the intermediate leg of the core, a magnetic keeper adjustably mounted on said loop end below said core, a resistor disposed below said keeper in series relation to said coil and a pair of terminals at the top of the casing.

4. A portable voltage multiplier for a portable watthour meter comprising a casing including insulating front and back plates having adjacent perimetral rabbet grooves, means including insulating standards for connecting said plates, a tubular insulating side wall surrounding said standards in said grooves, a non-magnetic bracket secured to said back plate, a laminated magnetizable core member and a coil therefor mounted on said bracket, a magnetizable keeper for said core adjustably mounted on said bracket, insulating spools mounted on said back plate, a resistor winding mounted principally on one of said spools but having a portion of its length for winding back and forth between said spools, terminals mounted on said side wall and conducting leads connected from one of said terminals to the principal spool, from the resistor between the spools to the coil and from the coil to another of said terminals.

5. In combination, a core member of substantially E-shape providing a pair of air gaps between the outer ends of the legs thereof, a keeper opposite, and extending transversely to, the middle leg thereof to directly affect each of said gaps, and means for adjusting and holding said keeper in adjusted position including only a single operating member for adjusting the keeper in the direction of said middle leg and holding the keeper in adjusted position.

6. In combination, a core member of substantially E-shape having inwardly-projecting lateral extensions on the outer ends of its end legs to provide relatively narrow air gaps next to the middle leg, surfaces of the legs and extensions lying in a common plane at right angles to the plane of the E-shaped core, a support spaced opposite said surfaces, a screw mounted in said support coaxially with said middle leg, and a discoidal keeper coaxially on said screw next to said surfaces in spaced parallel relation thereto and of greater diameter than the distance between said gaps.

In testimony whereof, we have hereunto subscribed our names this 11 day of December, 1929.

DOUGLASS A. YOUNG.
GEORGE J. WEY.
